UNITED STATES PATENT OFFICE.

OSCAR ZERK, OF CLEVELAND, OHIO, ASSIGNEE, BY MESNE ASSIGNMENTS, TO GEORGE W. BOWEN, OF AUBURN, NEW YORK.

GREASE-CUP.

1,265,861.

Specification of Letters Patent. Patented May 14, 1918.

Application filed May 26, 1918. Serial No. 769,851.

To all whom it may concern:

Be it known that I, OSCAR ZERK, a subject of the Emperor of Austria, residing at Cleveland, in the county of Cuyahoga and State of Ohio, have invented a certain new and useful Improvement in Grease-Cups, of which the following is a full, clear, and exact description, reference being had to the accompanying drawings.

- 0 This invention relates to grease cups of the type wherein there is a base, a cap threaded thereon and adapted to be rotated for feeding the grease, a detent device slideable and non-rotatably carried by the base and having a part co-operating with the cap for preventing the unintentional rotation thereof, and a spring tending to hold the detent device in yieldable engagement with the cap.
- 0 The invention is concerned particularly with the construction and arrangement of the described parts for producing an inexpensive, durable and efficient grease cup, which is particularly neat, pleasing and attractive in appearance.

In the drawing, Figure 1 is a side elevation of a grease cup embodying my invention; Fig. 2 is a vertical central section thereof; Fig. 3 is a plan view, and Fig. 4 is a plan of the detent device showing a portion of the operating spring therefor within it and showing the shank of the cup in section.

As shown in the drawing, 1 represents the base of the cup, which may conveniently be made of two connected stampings. One of these is a tubular stem or shank member having a hexagonal exterior 2, a reduced externally threaded nipple 3 at the lower end thereof, an internal bore 4 preferably enlarged at its upper portion 5, and upper and lower rabbets 6 and 7 near its upper end. The other stamping is the disk-like head 8 which has a beveled central opening of proper size to enable it to seat in the upper rabbet 7. When so seated it is rigidly secured to the shank member by outwardly upsetting the edge of the latter into the bevel-space or upon the upwardly presented adjacent surface of the head. The head 8 has a down-turned cylindrical flange 9 which is externally threaded.

10 indicates the cap, which has a cylindrical wall internally threaded to screw onto the threads of the flange 9. The cap

is shown as provided with nurling 11 and a wing 12, for facilitating the rotation thereof which parts may be employed or not, as desired. If the wing is employed, it is convenient to make it by stamping the head 60 portion of the cap into the form shown in Figs. 1 and 2.

20 indicates a detent device preferably formed of two nesting cups 21 and 22, which slidably surround the shank 2, the inner part 65 or cup 22 preferably having edge projections 23 for engaging notches 13 in the lower edge of the cap and the outer cup 21 extending above the cup 22 to cover and conceal the engaging edges of the cap and cup 22. The 70 central opening through one, preferably the upper, of the nesting cups 21 and 22, is made angular, corresponding to the shank 2 to prevent the detent device from rotating on the shank, but permitting it to slide 75 thereon. An annular recess is provided between the two members 21, 22, preferably by depressing a portion of the bottom of the member 21. Entrance is provided to this recess by means of an opening 28 in the 80 bottom of the member 22 adjacent to its central opening.

30 indicates the spring which draws the detent device toward the cap, and holds the projections 23 in engagement with the walls 85 of the notches 13. This spring is housed or concealed within the cups 21, 22, and is preferably an open-coil tension helix, so formed that each coil tends to move past the adjacent coil in the direction of the retraction. I may accomplish this by twisting or distorting the various coils, or, by taking an open-coil spring and turning it wrong-side-out to give an added twist to the coils and increase the tension effect. The 90 spring is anchored at its lower ends to the detent device by having its lowermost coil turned through the opening 28 into the annular recess between the members 21, 22, as shown at 31 in Figs. 2 and 4. The coil 100 is anchored at its upper end to the cup by having its uppermost coil occupying the annular groove provided by the rabbet 6 in the upper part of the shank 2 and the under face of the head 8. The tendency of 105 this spring to retract maintains the projections 23 in constant engagement with the lower edge of the cap, so that, as the cap is turned down to feed the grease, the projections periodically enter the notches and 110

lock the cap against displacement. The extensibility of the spring enables the cap to be turned down as far as desired.

In assembling the parts the spring is placed on the shank with its upper coil occupying the rabbet 6 before the head 8 is fastened to the shank. Then the upsetting of the end of the shank forms the complete cup and locks the spring in place. To secure the spring to the detent the bottom coil is drawn down below the hexagonal part of the shank and there is held while the detent is given a turn, the end of the spring passing through the opening 28 and into the recess between the members 21, 22.

It will be seen that my grease cup is extremely simple in construction. It may consist simply of the base, the cap, the detent device and the spring. As stated, the base may conveniently be a two-part stamping and the cap a single stamping. The two parts of the detent device may be first stamped into cup form and nested together and then the flange pressed inwardly to give the beaded form shown at 29 in the drawings. This bead not only increases the ornamental appearance of the grease cup, but effectively holds the two parts of the detent together so that they operate as a unit.

Having thus described my invention, what I claim is:

1. In a grease cup and in combination, a base, a cap threaded thereon to move about the axis of the same and lengthwise thereof, a part movable lengthwise of the base and having surfaces coating with complementary surfaces on the cap for holding the cap from accidental turning, means tending to yieldingly hold said part with the surfaces thereof engaged with the coating surfaces of the cap, and means inclosing the yielding means and the coating surfaces of the cap and said part for housing and concealing the same when the cap is engaged with the base, substantially as and for the purpose described.

2. In a grease cup and in combination, a base made of two pieces, one comprising a shank with an external recess, and the other a head secured to the shank above the recess, a cap having a surface for engagement by a detent member, a detent member on the base and a spring for holding the member in co-operative relation with the cap, said spring having a coil held between the head of the base and the opposing wall of the recess in the shank, substantially as and for the purpose set forth.

3. In a grease cup and in combination, a base, comprising a shank having two rabbets adjacent its upper end and a head having a central opening and occupying the uppermost rabbet, a cap, a detent device co-operating therewith, and a spring for operating the device, said spring having a coil

occupying the lower of said rabbets, the underface of the head coacting with the lower rabbet for providing a groove to receive said coil, substantially as and for the purpose described.

4. In a grease cup and in combination, a base, a cap turning on the base, the base including a head and a stem depending from the head, the head being formed with an opening through which a portion of the stem extends, and with a shoulder opposed to the lower face of the head, the stem having means at its upper end clamping on the adjacent upwardly presented part of the head, a holding member non-rotatably mounted on the stem and slidable lengthwise thereof, and coacting with the cap to hold it from turning, and a spring coiled about the stem and having the coil at its upper end clamped between the head and the shoulder of the stem and its lower end connected to the holding member to pull upwardly thereon, substantially as and for the purpose set forth.

5. A grease cup comprising a base including a head and a stem depending from the head, a cap threading on the head, a discoidal holding member non-rotatably mounted on the stem and slidable lengthwise thereof, the holding member being provided with a marginal annular flange projecting toward the head, an element fitting within the flange of the holding member and a coiled spring arranged to pull upwardly on the holding member and having one end thereof extending under said element, substantially as and for the purpose described.

6. A grease cup comprising a base including a head and a stem depending from the head, a cap threading on the head, a discoidal holding member non-rotatably mounted on the stem and slidable lengthwise thereof, the holding member being provided with a marginal annular flange projecting toward the head, an element fitting within the flange of the holding member, one of the fitted parts being formed with a groove, and said element being formed with an opening exposing the groove, and a coiled spring arranged to pull upwardly on the holding member and having one end thereof extending through said opening and into the groove and its other end anchored to the base, substantially as and for the purpose described.

7. A grease cup comprising a base including a head and a stem depending from the head, a cap threading on the head, a discoidal holding member non-rotatably mounted on the stem and slidable lengthwise thereof, the holding member being provided with a marginal annular flange projecting toward the head, a cup fitting within the flange of the holding member, and a coiled spring arranged to pull upwardly on

the holding member and having one end thereof extending under the cup and having its other end anchored to the base, substantially as and for the purpose set forth.

5. 8. A grease cup comprising a base including a head and a stem depending from the head, a cap threading on the head, a discoidal holding member non-rotatably mounted on the stem and slidably lengthwise thereof, the holding member being provided with a marginal annular flange projecting toward the head and with a groove in its bottom, an element fitting within the flange of the holding member and covering the grooves and having an opening exposing the groove, and a coiled spring arranged to pull upwardly on the holding member and having one end thereof extending through said opening and under said element and into the groove and having its other end anchored to the base, substantially as and for the purpose described.

9. In a grease cup, the combination of a shank having two rabbets adjacent to its upper end, a head having a downward flange and having a central opening whereby it seats in the upper rabbet, the upper end of the shank being upset to lock the head to the shank, a helical spring surrounding the shank and having its upper coil occupying the recess provided by the lower rabbet, a cap screwing onto the head, and a detent device coöperating with the cap under the influence of said spring.

10. In a grease cup, the combination, with the cup and cap, a detent device coöperating with the cap, and a retractile spring for holding the detent device and cap in engagement, said spring being a helix, each coil of which has a tendency to move past the adjacent coil in the direction of the retraction.

11. In a grease cup, the combination, with the cup and cap, a detent device coöperating with the cap, and a tension spring for holding the detent device and cap in engagement, said spring being a substantially cylindrical helix each coil of which has a tendency to move past the adjacent coil and the extreme coils of which are held in substantially parallel planes.

12. In a grease cup, the combination, with a cup and cap, a detent coöperating with the cap, and a tension spring for holding the detent device and cap in engagement, said spring being substantially a cylindrical open helix having a tendency to close farther than a helix with contiguous coils, the upper coil of the spring being anchored to the shank adjacent to the head of the cup and the lower coil being anchored to the detent device.

13. In a grease cup, the combination of a cup having a shank, a head and an annular groove about the shank adjacent to the head, a helical spring, each coil of which has a

tendency to move past the adjacent coil, said spring surrounding the shank and having its upper coil occupying said groove, a collar slidably but non-rotatably surrounding the shank and having the lower coil of the spring anchored to it, and a cap screwing onto the head and coöperating with the collar, the collar and cap being provided with an interacting projection and notch.

14. In a grease cup, the combination, with the cup, of a helical tension spring surrounding the shank of the cup and anchored to the cup at the upper end of the spring, a collar slidably but non-rotatably surrounding the shank and consisting of two shells nesting one within the other, the spring being anchored at its lower end to the collar by means of extending through an opening into a space between the shells, a cap screwing onto the cup, and interacting projections and notches on the collar and cap.

15. In a grease cup, the combination, with the cup and cap screwing one onto the other, of a collar slidably but non-rotatably surrounding the shank of the cup and coacting with the cap, a spring tending to force the collar into such coaction, the collar being made of two shells nesting one within the other, the outer shell being adapted to extend beyond the inner shell and form a dust protector for the cap.

16. In a grease cup, the combination, with the cup, of a cap screw-threaded thereon, a collar slidably but non-rotatably surrounding the shank of the cup, said collar being formed of two shells nesting one within the other, the inner shell coacting with the lower edge of the cup, and one of such members having a notch and the other a projection, and a spring pressing the collar toward the cap.

17. In a grease cup, the combination, with the cup and cap screw-threaded together, of a collar surrounding the shank of the cup and composed of two shells nested together, each shell having a flange, which flanges join the body of the shell by an outward bead, whereby the shells are locked together, a spring pressing the collar toward the cap, and an interacting notch and projection on the collar and cap.

18. In a grease cup, the combination of a cup, a cap screw-threaded thereon, a slidable collar surrounding the shank of the cup and made of two pieces of metal nested one within the other providing between them an annular recess about the shank, and a coiled tension spring surrounding the shank and anchored at its upper end to the cup and having its lowermost coil occupying the recess between the two members of the collar.

19. In a grease cup, the combination of a cup having an angular shank and a head with an external thread, a cap internally threaded screwing onto the head, a collar

slidable on the shank and comprising two cup-like members nested one within the other, coöperating projections and notches on the lower edge of the cap and the upper edge of the inner member of the collar, the outer member of the collar extending above the inner member to overhang the cap, and a spring pressing the collar toward the cap.

20. In a grease cup, the combination of a cup having an angular shank and an externally threaded head, an internally threaded cap screwing onto said head, a collar having an angular opening slidable on the shank and having a wall projecting toward the cap, said collar consisting of two cup-like members nested one within the other, an outward bead on the inner member nesting within a bead on the outer member, coöperating notches and projections on the lower edge of the cap and the upper edge of the inner member of the collar, and means for pressing the collar toward the cap.

21. In a grease cup, the combination of a cup having a shank and a head with an external thread, a cap having an internal thread screwing onto the head, a collar slidable on the shank and coöperating with the cap and comprising two members nested one within the other, one of said members being pressed away from the other about the shank to provide an annular recess, there being an opening into this recess through the inner member, a spring surrounding the shank and passing through said opening and having its lowermost coil occupying the recess, the uppermost coil of the spring being anchored to the cup, and coöperating projections and notches on the upper edge of the collar and the lower edge of the cap.

40. 22. In a grease cup, the combination of a cup having a shank and a head with an external thread, a cap having an internal thread screwing onto the head, a collar slidable on the shank and coöperating with the cap and comprising two members nested one within the other, one of said members being pressed away from the other about the shank to provide an annular recess, there being an opening into this recess through the inner member, a spring surrounding the shank and passing through said opening and having the lowermost coil occupying the recess, the uppermost coil of the spring being anchored to the cup, the two members of the collar having flanges extending toward the cup, the inner flange terminating short of the

outer flange, the inner flange being provided with a projection to engage the lower edge of the cap and the outer flange being adapted to overhang such cap.

23. In a grease cup, the combination of a cup having an annular portion and a down-turned externally threaded flange, whereby an annular recess is provided in the under face of the head, an internally threaded cap screwing onto the head, a collar slidable on the shank and having an up-turned wall to coöperate with the lower edge of the cap, the cap and wall having coacting notches and projections, said collar being made of two cups nested one within the other and held together by nesting outward beads, one of such cup-like members being pressed away from the other around the shank to provide an annular recess, and a coiled tension spring occupying the recess in the under face of the head and anchored at its upper end in a groove in the shank and near its lower end passing through an opening in the inner member of the collar into the annular recess thereof.

24. In a grease cup, the combination, of a cup having a shank with a bore and an angular exterior and a head made separable from the shank and secured at the upper end of the shank by reason of the shank being overturned onto the head, said head having a downward flange externally threaded, the shank having a groove in its outer side adjacent to the head, a collar made of two nesting cup-like shells slidable but non-rotatably surrounding the shank, the collar having an annular recess between its two portions, an inverted helical tension spring having its upper coil occupying the annular groove in the shank and its lower coil passing through an opening in the inner shell of the collar into the annular space between the collar members, an internally threaded cap screwing onto the head of the cup, said cap and the inner shell of the collar having a coacting notch and projection, and an outer shell of the collar extending beyond the inner shell and overhanging the wall of the cap.

In testimony whereof, I hereunto affix my signature in the presence of two witnesses.

OSCAR ZERK.
